PATENTED FEB. 19, 1907.

J. McGAVOCK.
ELECTRIC LIGHT SWITCH.
APPLICATION FILED APR. 8, 1906.

Fig. 1.

UNITED STATES PATENT OFFICE.

JAMES McGAVOCK, OF DENVER, COLORADO, ASSIGNOR TO THE NEW ENGLAND ELECTRIC COMPANY, OF DENVER, COLORADO, A CORPORATION OF COLORADO.

ELECTRIC-LIGHT SWITCH.

No. 844,533.

Specification of Letters Patent.

Patented Feb. 19, 1907.

Application filed April 6, 1906. Serial No. 310,305.

To all whom it may concern:

Be it known that I, JAMES McGAVOCK, a citizen of the United States of America, residing at the city and county of Denver and State of Colorado, have invented new and useful Electric-Light Switches, of which the following is a specification.

My invention relates to improvements in electric-light switches; and the objects of my invention are, first, to provide an electric-light switch that is either a single or three-way or double or multiple pole switch; second, to provide an instantaneous spring-throw and frictional brush-contact switch, and, third, to provide a simple durable electric-light switch that contains very few parts and that can be made cheaply and that is reliable and durable. I attain these objects by the mechanism illustrated in the accompanying drawings, in which—

Figure 1 is a vertical longitudinal sectional view through the supporting-casing of the switch on the line of a pair of the terminal poles, the operating mechanism being shown in side elevation. Fig. 2 is a central vertical longitudinal sectional view through the casing and mechanism. Fig. 3 is a central vertical transverse sectional view with the face-plate attached, the parts being in the position they assume immediately prior to being reversed by the action of the operating-spring. Fig. 4 is a plan view, the face-plate being removed. Fig. 5 is a perspective view of the yoke to which the operating mechanism is pivotally secured. Fig. 6 is a perspective view of one of the binding-posts, to which the contact-terminals are secured. Fig. 7 is a perspective view of one of the side plates of the oscillating lever. Fig. 8 is a perspective view of one of the contact-terminals. Fig. 9 is a perspective view of one of the rock-arms to which the push-arms are pivotally secured; and Figs. 10 and 11 are perspective views of plates which are pivotally secured, respectively, between the rock-arms and lever-plates and which confine the operating-springs.

Similar letters of reference refer to similar parts throughout the several views.

I preferably illustrate in the several figures of the drawings a three-way switch. In the drawings the numeral 1 designates a non-conductive casing, which I preferably make of porcelain and which consists of a hollow

casing having integral-formed closed end and open end. This casing is adapted to inclose and support my improved switch. In this casing I place four contact-terminal poles 2, 3, 4, and 5, each of which consists of a binding-post 6, which is made of any suitable conductive material, which is seated in a recess 7, formed in two of the opposite sides of the casing near the corners of the other two opposing sides. The opposite ends of these strips are turned at right angles to the body 65 of the strip to form a short step portion. This bottom step portion is secured to the inside of the bottom of the casing by a screw 8, and the top step contains a threaded aperture in which a binding-screw 10 is threaded, 70 that is adapted to connect to the terminal end of the ends of the four circuit-wires 11, 12 13, and 14. Apertures 15 are formed through the top edge of the opposite sides of the casing. The poles are secured to, through 75 which the ends of these circuit-wires are inserted to the binding-screws of the poles.

To the screws 8 of the binding-post I secure the contact-terminals 16 of these four poles, which consist of a blade of conductive material provided with a right-angled foot portion that rests on the foot of the binding-post and is secured to it by the screw 8. The body of this contact-terminal rests against the body of the binding-post, and at its opposite end spring-wings 17 are formed, which are made of an electric resilient or springing conductive metal, such as spring-brass. These wings are folded toward each other to stand close together, and a narrow tapering 90 entrance-guideway 18 is formed at the upper and lower ends of the wings, which will prevent the brushes from catching as they pass in between the wings, as will hereinafter be shown. The four poles, which comprise two 95 sets of poles in this three-way switch, are all identical in construction. Across the top of the open end of the casing I secure a plate 20 by screws 21 to the edges of the sides of the casing. This plate extends beyond the casing a short distance at each end, which contain screw-receiving apertures by which the casing may be secured to a wall or partition in which it is placed. To the under side of this plate I secure the center portion of a 100 yoke 22, the ends of which depend from the plate and contain apertures 23, in which I pivotally secure one end of an oscillating or

tilting cage-shaped lever 24. This cage consists of two side pieces 25, each of which is pivoted at its upper end in the apertures 23 of the yoke 22 by a pin 26, while their lower ends are connected by a pin 26^A. A pin 22^A extends through the yoke just above the cage 24, and upon this pin I pivotally secure two crescent-shaped rock-arms 27 and 28, which I place inside of the sides of the cage 10 and pivot them in a central aperture 29, formed substantially in alignment with the ends of these crescent-shaped levers. The ends of these two rock-arms are arranged to register opposite each other, and in them I 15 form two apertures, to which I pivotally attach one of the ends of two push-pins 30 and 31, to the opposite ends of which I secure two push-buttons 32 and 33. These push-buttons extend loosely through two apertures 34 20 and 35, which I form in the plate 20, and act as guide-apertures for them. Below the aperture 29 in the rock-arms I form an aperture 36, in which I pivotally secure a tilting plate 37, and near the lower end of the cage 25 I pivotally secure a similar tilting plate 38. These two tilting plates I connect together by a pin 39, which is rigidly connected to the plate 38, but has a sliding movement through an aperture 37^A in the plate 37, and around 30 the pin between the plates I mount a coiled expansive spring 40, which oscillates with its cage. This spring is under sufficient expansive pressure to always throw the rock-arms and the cage to one side of their pivotal centers when the arms have been pressed down a sufficient distance by one of the push-buttons, and this spring always holds the cage and the rock-arms tilted to one side of the pivotal center of the rock-arms and yoke. 35 This arrangement normally holds one push-button projecting above the plate 20 and the other practically even with its surface. Pins 22^B extend through the yoke 22, one on each side of the pin 22^A, and these pins act as 40 stops to limit the movement of the rock-arms and of the cage when they are thrown from one position to another by the action of the spring 40.

To the opposite ends of the pins 26 that 50 project beyond the yoke I rigidly secure double-ended make-and-break contact-brushes 41 and 42, both of which consist of a hub portion with thin knife-blade contacting terminals 43, projecting from the opposite sides of the hub portion. These make-and-break knife-blade double-ended contact-brushes are arranged in the three-way switch 55 with one brush in contact with the poles, and I have illustrated the brush 41 in contact 60 with the poles 2 and 3 and with the contact-blades of the other brush 42 at an oblique angle to the brush 41 and with one of its contact-blades a short distance above and the other contact-blade a short distance below 65 its co-operating poles 4 and 5, preferably as

shown. Consequently one contact-brush will stand in contact with its poles and the other contact-brush will be in position to be thrown in contact when the one that is in contact is thrown out of contact, and vice 70 versa.

The operation is as follows: When the push-button 32 is pushed down, the contact-brush 41, which is shown in contact with the poles 2 and 3, is thrown out of contact with them, one blade of the brush rising out of the spring-wings of the pole 1 and the other blade moving down out of the spring-wings of the pole 2, while the brush 42 is thrown in, the expansive tension of the spring being sufficient 80 when it is thrown over the center of the rock-arms and cage to cause it to drive the knife-blades of this brush into the spring-wings of the poles 4 and 5. This downward movement of the push-button 32 forces the rock-arms down, which causes the plate 37 to slide on the pin 39 and compresses the springs 40, the pin at the same time being moved to a point where it is in line with axis of the rock-arms, and as it passes to one side of this line 90 the spring instantaneously expands, causing the rock-arms to be quickly thrown to the opposite of their original position and the cage to the opposite of its original position, driving the knife-blades of the brush 42 into 95 the spring-wings of the poles 4 and 5 and pushing the push-button 33 up above the plate. Then when this push-button is pressed down the contact-brush 42 is thrown out and the contact-brush 41 is forced again 100 between the wings of the poles 2 and 3. A face-plate 44 may be placed over the end of the casing and secured by screws to the supporting-plate 20. The circuit-wires 11, 12, 13, and 14 are arranged in opposite sets, the wires 11 and 12 connecting with the poles on one side of the switch and the wires 13 and 14 connecting with the pole on the opposite side.

In the three-way switch the bottom of the 110 casing is provided with a recess 46, which is formed transversely across one end of it and connects with the screw-holes in which the screws 8 of the binding-post and terminal are secured, and in this recess a strip of material 48 is placed, that is clamped in the recess by the screws 8, which extend through apertures in its ends, and a cross-circuit is thus formed between two cross-poles. The switch is then ready to be operatively connected in an electric-light circuit in a well-known manner.

In order to make a single-pole switch, this cross connection and the poles and brush and the circuit-wires on one side of the yoke in 115 the casing are left off entirely, and in order to make a double-pole switch both brushes are set parallel with each other and in contact with both sets of poles; but the cross-circuit strip 48 is left off when one push-but- 120 125 130

ton and the rock-arms and cage and spring are in operative position to throw them out at the operation of the projecting push-button.

Having described my invention, what I claim as new, and desire to secure by Letters Patent, is—

1. In an electric-light switch, a supporting-casing, terminal poles operatively mounted in said casing, a support in said casing, rock-arms mounted in said support intermediate of their ends, reciprocating push-buttons in said support connected to the opposite ends of said rock-arms, an oscillating lever pivotally connected to said support, a spring which presses at one end against said oscillating lever and at its opposite end against said rock-arm below its pivotal center in said support, contact-brushes connected to said oscillating lever and arranged in operative make-and-break relation to said poles, as set forth.
2. In an electric-light switch, a support having a yoke secured thereto; an oscillating lever pivoted to said yoke; rock-arms pivoted to said yoke above said lever; push-arms connected to the ends of said rock-arms; an apertured plate pivoted between said rock-arms; a plate pivoted to the lever, and a pin secured to the latter plate and extending through the aperture in the other plate; a coiled spring upon said pin, between said plates, and brushes operated by said lever, in combination with a suitable casing, having terminal poles located in the path of said brushes.

3. In an electric-light switch, the combination with a casing having terminal poles, of a support secured to said casing, having a yoke; a lever comprising side plates pivot-

ally secured at their upper ends to the yoke; 40 a pair of similar-shaped rock-arms, pivoted centrally to said yoke, above said lever; push-arms secured between the adjacent ends of said rock-arms; an apertured plate, pivoted between said arms below their pivotal 45 point, a plate pivoted between the said plates of the lever, and below the apertured plate, having a rigid pin which extends up through the aperture in the upper plate; a coiled spring on said pin, between said plates, and 50 brushes rigidly secured to the pivot-pins of said side plates, and in the path of the terminal poles.

4. In an electric-light switch, a support having a yoke; a lever comprising similar-shaped side plates, pivoted to the yoke by independent pivots, and brushes rigidly secured upon the projecting ends of the pivots; a pair of rock-arms centrally pivoted to said yoke, above the lever, having push-arms 55 pivotally secured between their ends; an apertured plate pivotally secured between the rock-arms below their pivotal point and midway of their length; a plate pivotally secured between the side plate of the lever, below the apertured plate, having a rigid pin which extends up through the apertured plate; a spring surrounding said pin, between the plates, and stops for limiting the 60 throw of the rock-arms and of the lever in 65 either direction.

In testimony whereof I affix my signature in presence of two witnesses.

JAMES McGAVOCK.
